ADJUSTABLE FINISHING MACHINE

Gustave A. Carlson, Detroit, Mich.

Application August 23, 1935, Serial No. 37,524

29 Claims. (Cl. 51—166)

My invention relates to improvements in a finishing machine in which the finishing member is adjustably mounted and the objects of my improvements are, first, to provide an adjustable finishing machine in which a finishing member is provided with mechanism enabling the finishing member to be adjusted with a universal movement; second, to provide an adjustable finishing machine having a column support and by which the finishing member is swivelly supported, relative to a horizontal plane, at a point removed from the axis of the column support; third, to provide a finishing machine having a finishing member adjustably supported in an overhanging position from an upright column support member; fourth, to provide a finishing machine having a finishing member adjustably mounted on an upright column mounted on a pair of slides movably mounted one upon the other and adapted to move in directions at right angles to one another; fifth, to provide a finishing machine having a finishing member pivotally mounted on a swivelly mounted support mechanism; sixth, to provide a finishing machine having a finishing member actuated in a pivotal movement by resilient means; seventh, to provide a finishing machine having a pivotally mounted finishing member mounted on a swivel mechanism and provided with means for causing the finishing member to yieldingly engage the member to be finished; eighth, to provide a finishing machine with a finishing member pivotally mounted together with an electric motor assembly adjustably mounted about the pivot of the finishing member; ninth, to provide a finishing machine having a finishing member revolvably mounted on a pivot support and provided with adjustable means for causing the finishing member to yieldingly engage the member to be finished; tenth, to provide a finishing machine having a finishing member adjustably mounted in an up and down direction on a column support; eleventh, to provide a finishing machine having an upright column with a finishing member adjustably mounted to be rotated around the column by manually operated mechanism located at the top of the column; twelfth, to provide a finishing machine having a finishing member rotatably mounted on a plurality of rotatably mounted mechanisms; thirteenth, to provide a finishing member operatively mounted on support mechanism rotatably mounted on an upright column together with means operatively mounted within and extending longitudinally of the column for moving the support mechanism along the

upright column; fourteenth, to provide a finishing machine having a finishing member adjustably mounted on an upright column and provided with keyway mechanism extending longitudinally of the column for preventing the support member from turning about the column; fifteenth, to provide a finishing machine having a column together with a collar mechanism adjustably mounted to move longitudinally thereof and retained against movement around the column together with a finishing member support mechanism rotatably mounted on the collar mechanism; and sixteenth, to provide a finishing machine having a finishing member movably supported on a column with means permitting adjustment of the finishing member together with its supporting mechanism for substantially the total length of the column.

I attain these objects by the mechanism illustrated in the accompanying drawings, in which—

Figure 1 is a side elevation of the adjustable finishing machine; Fig. 2, a side elevation of the adjustable finishing machine taken substantially at right angles to the view disclosed in Fig. 1; Fig. 3, a plan view of an adjustable finishing machine; Fig. 4, a partial sectional view of the finishing machine taken on the line 4—4, Fig. 1; Fig. 5, a partial sectional view of a finishing machine taken on the line 5—5, Fig. 1; Fig. 6, a partial side view of the finishing machine taken along the line 6—6, as indicated in reference to Fig. 1; Fig. 7, a partial side elevation of the column or spindle of the finishing machine; Fig. 8, a sectional view of the mechanism for supporting the electric motor assembly, said sectional view being taken on the line 8—8, Fig. 2; Fig. 9, a partial sectional view of the finishing machine taken on the line 9—9, Fig. 2; Fig. 10, a partial view disclosing the finishing member of the finishing machine in relation to an object undergoing a finishing operation; and Fig. 11, a partial side view of the finishing machine disclosing the mechanism for adjustably supporting the electric motor assembly together with the electric motor assembly operatively connected with the finishing member driving mechanism.

Similar numerals refer to similar parts throughout the several views.

The adjustable finishing machine is provided with the base portion or member 1 having upwardly and inwardly inclined or tapered side walls together with the flange 2 through which extend the screws 3 for securing the base member 1 to a floor or similar supporting structure 4.

5 The base member 1 is provided with the ways or V's 5 in which is movably mounted the slide 6 which is provided with a V portion for fitting within the V's 5, the gib 7 being interposed between the V portion of the slide 6 and the V's 5 of the base member 1 to provide means for taking up wear, the gib 7 being adapted to be adjustably secured by the screws 8 together with the lock nuts 9.

10 The base member 1 will be provided with the boss 10 which is threadably engaged by the shaft 11 which is rotatably mounted in the boss portion 12 of the slide 6 and is retained longitudinally therewith by the collars 13 and 14, the shaft 11 being provided with the square end 15 which is adapted to receive the hub or boss 16 of the crank 17 provided with the handle portion 18. The slide 6 will be provided with the recess or chamber 19 which provides operating clearance 20 space for the shaft 11 and the boss 10.

25 The slide 6 is provided with the ways or V's 20 extending longitudinally substantially at right angles to the ways or V's 5 of the base member 1. A second slide 21 is mounted on the slide 6 with a V portion movably mounted in the ways or V's 20 of the slide 6, the gib 22 being interposed between one side of the ways or V's 20 and the V portion of the slide 21 to take up wear, the gib 22 being adjustably secured by the screws 23 and the lock nuts 24. The slide 6 is further provided with the boss 25 which extends within the recess or chamber 26 of the slide 21 and is threadably engaged by the shaft 27 which extends therethrough and is revolvably mounted 35 in the boss portion 28 of the slide 21, the shaft 27 being provided with the square end 31 which is adapted to receive the hub portion 16 of a crank 17 which is provided with the handle portion 18.

40 The column, support, or spindle 32 is preferably cylindrical in shape and is of hollow or tubular construction and has the chamber 33 extending therein and therethrough. The column 32 is provided with the flange 34 at its base, said 45 flange 34 resting on the upper surface of the slide 21 and being secured thereto by the screws 35 extending therethrough and engaging the slide 21.

50 The column 32 is provided with the slot or keyway portion 36 which extends for the greater portion of the longitudinal height or length of the column 32.

55 The housing, collar or nut member 37 is provided with the bore 38 which engages and fits around the outer cylindrical surface of the column 32 and is adapted to be slidably moved up and down thereon.

60 The nut member 37 is provided with the collar portion or shoulder 39 together with the extension or pilot portion 40 which extends and fits within a bore of the housing member 41, the housing member 41 having its lower surface engaging and resting upon the surface 42 at the upper side of the collar or shoulder portion 39 65 of the nut member 37, the pilot portion 40 being provided with the bore 40A which extends around and clears the outer cylindrical surface of the column 32.

70 The upper end of the extension portion 40 of the nut member 37 may also, if desired, contact the upper end surface of the bore of the housing member 41 engaged by the extension portion 40 of the nut member 37 to provide additional support for the housing member 41 thereon.

75 The nut member 37 is provided with the key-

way or slot 43 in which is fixedly secured the key member 44 which extends through the keyway 43 of the wall portion of the collar 39 of the nut member 37 and into and through the slot or keyway 36 of the column 32, thus preventing any 5 turning or rotation of the nut member 37 relative to the column 32 and at the same time allowing the nut member 37, together with its supporting mechanism, to move longitudinally relative to the column 32, the key member 44 movably engaging the slot or keyway 36 in its travel up and down the column 32. The key member 44 is secured to the collar 39 of the nut member 37 by the screw 45 which extends through the key member 44 and threadably engages the collar 15 portion 39 of the nut member 37.

20 The housing 41 is provided with a substantially flat surface 46 at one of its sides for engaging a similar flat surface on the support bracket 47.

25 The housing 41 is provided with the slot 48 through its side wall adjacent the surface 46, said slot 48 extending from the lower surface of the housing 41 to a point adjacent the upper end surface of the bore for receiving the pilot portion 49, the slot 48 providing the housing member 41 30 with resilient characteristics to permit the housing 41 to be clamped to a snug or tight engagement between the extension 40 of the nut member 37 and the bore of the housing 41 engaging the extension portion 49, the clamping action being attained by the clamp screw 49 extending through one side portion of the housing 41 adjacent the slot 48 to threadably engage the opposite side portion of the housing 41.

35 The support bracket 47 is provided with the flanges 50 which have their inner surfaces engaging the surface 46 of the housing 41 and are secured thereto by the screws 51, the support bracket 47 being further provided with the slot 52 extending through and between the flanges 50 40 to allow the support bracket 47 to have certain resilient characteristics sufficient to allow for the clamping action of the clamp screw 49 without stressing or injuring the support bracket 47 and without necessitating the removal of the 45 support bracket 47 from the housing member 41 when the housing member 41 is clamped by the clamp screw 49 to a rigid engagement with the extension portion 49 of the nut member 37. The nut member 37 is provided with the lug or boss 50 53 which is provided with the threaded hole 54 which is located concentrically with the cylindrical surface of the column 32 and the axis of the housing 41 which receives the extension portion 49 of the nut member 37, the boss or lug 53 being 55 rigidly connected to the inside wall of the nut member 37 by means of the web or flange 55, the web or flange 55, together with the boss or lug 53, being located above the key member 44.

60 The threaded hole 54 of the boss or lug 53 is 65 revolvably engaged by the threads of the shaft 55 which thus is supported in the boss or lug 53 at one of its end portions in such manner as to provide, together with the bearing assembly 57, a two point support to absorb thrust loads in a direction transverse to the axis of the shaft 55, the bearing assembly 57 being of the thrust bearing type which also absorbs the load or weight of the shaft 55 longitudinally thereof together with the parts secured thereto, such as the worm gear 58, 70 which is secured to the shouldered or extension portion 59 of the shaft 55 by the nut 60. The bearing assembly 57 is retained and supported in the bore 61 of the housing 62, the worm gear 58 having its lower side surface engaging the upper 75

side of the bearing assembly 57. The housing 62 is provided with the chamber 63 which is closed at its upper end by the cover member 64 secured to the upper surface of the housing 62 by the screws 65. The housing 62 is provided with an extension or pilot portion 66 which extends within and engages the bore 67 of the housing 68 which is provided with a flange 69 for resting in a supported position on the surface 70 at the upper end or top of the column 32, the housing 68 being secured to the column 32 by the screws 71, the screws 71 extending through the flange 69 threadably engaging the column 32.

The housing 68 is provided with the extension or pilot portion 72 which fits within and engages the bore 73 at the upper end of the column 32. The extension or pilot portion 66 of the housing 62 is provided with the clearance hole or bore 74 into and through which extends the shaft 56.

The housing 62 is provided with suitable boss portions within the chamber 63 and in which is revolvably mounted the shaft 75 upon which is fixedly secured to revolve therewith the worm 58, the shaft 75 being provided with the squared end 77 which is adapted to receive the hub portion 16 of one of the lever members 17 having the handle portion 18.

Also the housing 68 is provided with a suitable boss portion 78 in which is adjustably mounted the screw 79 which extends through said boss portion 78 and wall portion of the housing 68 to allow its pointed end to engage the extension or pilot portion 66 of the housing 62 and to lock the housing 62 in any selected adjusted position and at the same time allowing said housing 62 and its mechanism contained therein to be adjustably moved around the axis of the shaft 56 as desired for different operating positions.

It is to be understood that, whereas I show three lever members 17 at different points on my adjustable finishing machine, one lever member 17 is adapted to fit all of the squared ends 15, 31 and 77, thus making the one lever member 17 suitable for operating the various shafts 11, 27 and 75, as disclosed.

The support bracket 41 is provided with the downwardly extending flanges 80 and is further provided with a suitable boss portion at its upper wall portion having the bore 81 extending therethrough for receiving the bolt 82 therethrough, the bolt 82 further extending through the bore 83 of the housing 84 which is thus swivelly or pivotally mounted on the stud 82, the stud 82 being retained by the nut 85 located between the flanges 86 of the support bracket 41.

The housing 84 is provided with the chamber 86 which provides operating space for the worm gear 87 which is mounted on the extension portion 88 which extends into the chamber 86 and forms a part of the shaft or stud portion 89 which further is fixedly connected with and forms a portion of the bracket 90, the bore of the housing 84 for receiving the shaft 89 extending substantially at right angles to the axis of the bolt 82 and being located sufficiently to one side of the bolt 82 to provide for the stud 89 to pass the bolt 82, as disclosed in Figs. 3 and 9.

It is to be noted that the shaft 89 will thus be swivelly mounted in and relative to the housing 84 which in turn is swivelly mounted on and relative to the bolt 82. The worm 91 is fixedly secured and mounted on the shaft 92 which is rotatably mounted and retained in suitable boss portions of the wall portions surrounding the cham-

ber 86 of the housing 84 and is provided with the squared end 93 which is adapted to receive the hub or boss portion 94 of the lever member 95 provided with the handle portion 96, the worm 91 being adapted to rotatably engage and operate 5 the worm gear 81.

The chamber 86 of the housing 84 is closed by the cover member 97 which is secured to the housing 84 by the screws 98. The wall portion surrounding the bore of the housing 84 for receiving 10 the shaft 89 is provided with the slot 99 at one of its sides together with the boss portions 100 which are adapted to receive the screw 101 which provides means for utilizing the resilient characteristics of the housing 84 provided with the slot 15 99 and the bore for receiving the shaft 89 to clamp said bore around the shaft 89 to fixedly secure it thereto.

The housing 84 is provided with the boss or flange portion 102 at its lower side for engaging a 20 similar shaped surface on the upper side of the support member 47 and is thereby supported in its swivel or pivotal motion on the support bracket 47.

The bracket 90 is provided with the boss 103, 25 through which extends the shaft 104 which may be fixedly secured therein as by a press fit or similar means, the shaft 104 extending beyond the end surfaces of the boss 103 and is supported in the bearing assemblies 105, the shaft 104 extending through the bores 106 of the brackets 107 which are provided with the bores 108 in which the bearing assemblies 105 are mounted, said bores 108 further receiving the pilot portions 109 of the cap or cover members 110 which are secured to the bosses 111 of the brackets 107 by the screws 112. The cap members 110 thus secure the outer races of the bearing assemblies 105 in their mounted positions. The inner race members of the bearing assemblies 105 are secured to extension portions of the shaft 104 by the washers 113 and nuts 114.

It is to be noted that the brackets 107, together with the cap members 110 will be mounted on the bearing assemblies 105 and will thus be 45 swivelly mounted relative to the shaft 104 and the boss 103, the bosses 111 being provided with thrust surfaces at their inner sides for engaging the thrust surfaces at the outer ends of the boss 103. The brackets 107 are provided with flange 50 portions 115 which are secured to the boss portions 116 of the housing 117 by the screws 118.

The housing 117 is thus adapted to pivot or swivelly move about the axis of the shaft 104 as disclosed in Fig. 2 and the housing 99 will be 55 substantially shaped and provided with an undercut portion as disclosed by the line 119 to provide an operating space, at its under side, for the housing 117 when said housing 117 is in its uppermost position as disclosed in Fig. 2.

The housing 117 is provided with the opening or passage 120 extending therethrough, said passage 120 being provided with the bores 121 at its outer ends for receiving the outer race members of the bearing assemblies 122, the inner race 65 members of said bearing assemblies being mounted on extension portions of the shaft 123 which extends entirely through the housing 117 and outwardly from and beyond each of its end surfaces, the inner race members of the bearing assemblies 122 being suitably secured by the nuts 124 threadably engaging suitable portions of the shaft 123. The cap members 125 are suitably secured to the end surfaces of the housing 117 by the screws 126.

The shaft 123 is provided with the extension portion 127 at one of its ends and upon which is fixedly secured the pulley member 128 by the washer 129 and the nut 130.

- 5 The shaft 123 is provided at the other of its ends with the extension portion 131 upon which is mounted the finishing member 132 which may be a buffing wheel, grinding wheel, polishing wheel, or similar finishing member, the finishing member 132 being secured by the washers 133 together with the nut member 134 threadably engaging the outer end of the extension portion 131 of the shaft 123.

The electric motor assembly A is provided with 15 the pulley member 135 which is suitably secured to the drive shaft 136 of the electric motor assembly A by the nut 137, the pulley member 135 being operatively connected with the pulley member 128 by the belts 139 which engage the grooves 20 of the pulleys 135 and 128 and thus provide driving means by which the electric motor assembly A drives the shaft 123, together with the finishing member 132. The electric motor assembly A is further provided with the flange or feet portions 25 140 which are secured to the flange 141 of the bracket members 142 by the screws 143 and nuts 144. The brackets 142 are provided with the boss portions 145 which are provided with the bore 146 through which extends the screws 147 30 which thus swivelly and pivotally support the brackets 142 together with the electric motor assembly A and allow said bracket 142 and the electric motor assembly A to be pivotally moved about the axis of the screws 147 to provide means for 35 adjusting the tension on the driving belts 139, the screws 147 threadably engaging the cap or cover members 110.

In order to lock the tension of the driving belts 139 in their adjusted positions, one of the brackets 40 142 is provided with the boss 148 in which is pivotally supported the end of the shaft or stud 149 as at 150, the shaft 149 extending through a suitable opening in the rib or flange 151 of the brackets 147, said rib 151 being connected 45 between the boss portion 111 and the flange 115.

After the electric motor assembly A, together with its brackets 142, have been adjusted to their proper position for tensioning the driving belts 139, the shaft 149 is locked in place by the nuts 50 152 which threadably engage the shaft 149 on opposite sides of the web or flange 151.

In order to provide further tension means for causing the finishing member 132, to engage a member to be finished, such as the hub cap 153 55 as disclosed in Fig. 10, the boss 103 is provided with the web, lug, extension or boss portion 154 which is rigidly connected with the boss 103 and extends into the chamber 155 formed by the hollow or rectangular box like portion 156 which 60 connects and is fixedly secured to the brackets 147, the boss portion 156 extending beyond and surrounding the lug 154 of the boss 103.

The stud 157 will be suitably and fixedly secured in the lug 154 and will extend through a 65 suitable opening in the lower wall portion 158 of the boss 156 and will be provided with the spring or resilient member 159 which will be secured thereon by the nut 160 threadably engaging the outer end of the stud 157, the spring 159 thus exerting a tension against the wall portion 158 of the boss 156 and tending to urge the wall portion 158 toward the lug 154 with a consequent downward movement of the finishing member 132, together with its supporting mechanism.

70 75 In a similar way the stud member 161 will be

suitably secured in the upper wall portion 162 of the boss 156 and will extend through a suitable opening in the lug 154 and if necessary through a suitable clearance opening 163 provided in the wall portion 158 and in a similar way the spring 5 or resilient member 164 will be mounted on the outer end of the stud 161 and will be secured thereon by the nuts 165 threadably engaging the outer end of the stud 161 and to provide for the use of a shorter spring than would otherwise be 10 the case, the bushing or collar member 166 may be slidably mounted on the outer end of the stud 161 and interposed between the spring 164 and the lug 154 to exert an effort to urge the wall portion 162 toward the lug 154 and resulting in 15 a tendency to urge or move the finishing member 132 and its operatively supporting parts upwardly and swivelly or pivotally about the axis of the screws 147.

For purposes of illustration the hub cap 153, 20 or similar member, to be finished, may be suitably mounted and retained on a supporting member 167 of a supporting or conveyor mechanism which will support, move and feed a plurality of the hub caps or similar members 153 past the 25 finishing member 132.

The electric motor assembly A is provided with a suitable electric cable 168 for connecting with a source of electric power to operate the electric motor assembly A.

In operation the electric motor assembly A will drive the pulley member 135, which will in turn, through the medium of the driving belts 139, drive the pulley member 128, which in turn drives the shaft 123 together with the finishing member 30 35 132 mounted thereon.

Due to the contour of such members as the hub cap 153 or similar members, it is necessary to provide various operating positions for the finishing member 132 and this is possible in my 40 invention due to various adjustably mounted and operating portions thereof. In selecting the best operating position for the finishing member 132, as dictated by the shape or contour of the members which are to be finished, the operator 45 will fit one of the handle members 17 to the square end 15 of the shaft 11 and by revolving the shaft 11 with the lever member 17, the slide 6, together with its supported mechanism, will be moved to the proper position which will facilitate engagement with the member 153 by the 50 finishing member 132.

In order to further facilitate the position of the finishing member 132, the operator may utilize the same lever member 17 by fitting it 55 on the square end 31 of the shaft member 27 which will enable the slide 21, together with its supported mechanism, to be moved in a plane extending at right angles to the plane of movement of the slide 6, thus providing further adjustable ability for moving the finishing member 132 to its desired and required position.

The operator now places the lever member 17 on the square end 77 of the shaft 75 and by operating the shaft 75, the worm 76 will operate 65 the worm gear 58 which will in turn drive the shaft 56 which will cause the boss 53, together with the collar 37 and its supported mechanism to travel up or down the column 32 as desired, for the positioning of the finishing member 132 70 relative to the work to be finished, the key 44 preventing the collar 37 from rotating about the axis of the column 32.

Also in conjunction with the operation of the shaft 75 by means of the lever 17, the screw 79 75

may be loosened to permit the housing 62 and its supported mechanism to be rotated about the axes of the shaft 56 and the worm 58 to provide the desired position for best and convenient operation of the lever member 17 on the shaft 75 by the operator.

After the finishing member 132 has been positioned in an up and down position, by the means which has just been described, and by travelling up and down the column 32, the support bracket 47, together with the housing 41 may be swivelly or pivotally moved together with its supporting mechanism, about the axis of the shaft 56 and the column 32 and after the selected position of the finishing member 132 has been attained in this operation, the housing 41, together with its supported mechanism, may be locked in its adjusting position by means of the clamp bolt 49.

The next portion of the set up operation is to position the housing 34, together with its supported mechanism, in its proper position about the axis of the bolt 82 by swivelly or pivotally moving the housing 34 and its supported mechanism about the axis of the bolt 82 to similar positions as indicated at 171 and 172 in Fig. 3, after which the bolt 82, together with the nut 85, may be utilized for clamping the housing 34 and its supporting mechanism in its adjusted position about the axis of the bolt 82. Then the operator is able, by means of the lever member 95, to operate the shaft 92 which will in turn revolvably operate the worm 91 which will operatively engage and revolve the worm gear 87 which will in turn cause the shaft 89 to be rotated together with the bracket 99 and its operatively supported parts, about the axis of the shaft 89, thus providing a further swivel or pivotal movement which will enable the finishing member 132 to be placed in different adjusted positions or operating positions such as indicated by the dotted lines 169 and 170 in Fig. 1, said adjusted and similar positions 169 and 170 being accomplished by adjustably moving the finishing member through an arc having a considerably less radius than is the case where the finishing member is swivelly moved in a vertical plane having its pivot point located adjacent the column 32 as is conventionally done in present and similar mechanical equipment.

Now the finishing member 132 will be further urged to the positions as indicated by the dotted lines 173 and 174 in Fig. 11, by means of the springs 159 and 164 according to the tension placed upon them by the nuts 160 and 165.

Also this operation of positioning the finishing member 132 by the springs 159 and 164 and the nuts 160 and 165 will determine the amount of tension which is desired for the finishing member 132 to exert against the hub cap or similar member 153, and it is to be noted that this pressure exerted by the finishing member 132 against the member 153 is thus controlled to predetermined amounts and is not accomplished by balancing mechanisms utilizing the electric motor assembly A or similar means for balancing purposes as is the case in conventional mechanisms.

Also if desired, when it is desired to operate my adjustable finishing machine with the finishing member 132 held in a fixed position and without the resilient means for actuating same in its contact with the member to be finished, then the screws 175 and 176, which are respectively mounted in the wall portions 158 and 162, may be adjustably operated until they engage the lug 154 which will fixedly position the boss member

156 relative to the lug 154, thus further fixedly positioning the brackets 107 together with the housing 117 and the finishing member 132 in a fixed position against swivel or pivotal movement about the bolts 147 and in the desired position for contacting and engaging the hub cap or similar member 153.

I claim:

1. In an adjustable finishing machine, the combination of a slide member movably mounted, a second slide member movably mounted on said first mentioned slide member, a tubular column mounted on and extending upwardly from said second slide member and provided with a keyway extending through its side wall for the greater portion of the length of said tubular column, a nut member slidably mounted on said tubular column and provided with a boss portion extending within said tubular column, a key member secured to said nut member and engaging the keyway of said tubular column, a housing structure mounted at and closing the upper end of said tubular column, a shaft suitably supported at one of its ends in said housing structure and extending into said tubular column, said shaft threadably engaging the boss portion of said nut member, manually operated means for rotating said shaft, a second housing structure rotatably mounted on said nut member, clamp means for securing said second housing structure on said nut member, a third housing structure swivelly mounted on said second housing structure, a bracket member swivelly mounted on said third housing structure and adapted to swivel about a horizontal axis, said bracket member being provided with a boss portion having a bore therethrough, a manually operated means for swivelling said bracket member, a second shaft mounted in the bore of the boss portion of said bracket member, a second bracket member pivotally mounted on said shaft, a housing supported on said second bracket member, a third shaft rotatably supported in the housing supported on said second bracket member, electrically operated means for driving said third shaft member, a third bracket member adjustably and pivotally supported by said second shaft and adapted to support said electrically operated means, and resilient means for actuating said second bracket member together with its supported mechanism about said second shaft.

2. In an adjustable finishing machine, the combination of a pair of slide members movably mounted, one upon the other, said slide members moving in directions substantially at right angles to one another, an upright tubular column mounted on the upper of said pair of slide members, a nut member slidably mounted on said upright tubular column, means for slidably operating said nut member, said means extending within said upright tubular column, a support structure rotatably mounted on said nut member, and a second support structure mounted on said first mentioned support structure and adapted to swivel about a horizontal axis, a finishing member rotatably mounted and swivelly supported on said second support structure, and electrically operated means for driving said finishing member.

3. In an adjustable finishing machine, the combination of an upright tubular member movably mounted and provided with a keyway extending longitudinally thereof, a nut member slidably mounted on said upright tubular member and provided with a boss located within said

- upright tubular member, a key mounted on said nut member and engaging the keyway of said upright tubular member, a shaft rotatably mounted and extending within said upright tubular member and engaging the boss of said nut member, means for rotating said shaft, a support structure rotatably mounted on said nut member, a second support structure rotatably mounted on said first mentioned support structure, a third support structure rotatably mounted on said second support structure, a finishing member swivelly mounted on said third support structure, and means for driving said finishing member.
4. In an adjustable finishing machine, the combination of an upright tubular member having a keyway extending longitudinally thereof, a nut member provided with a pilot portion together with a shoulder there adjacent, said nut member being provided with a boss portion within said upright tubular member, said nut member being provided with a web portion for connecting said boss portion with the wall portion of said pilot portion of said nut member, said web portion extending through said keyway of said upright tubular member, shaft means rotatably supported and engaging said boss portion of said nut member, means for operating said shaft means, a support structure rotatably on the extension portion of said nut member and resting on said shoulder adjacent thereto, a finishing member swivelly supported by said support structure, and means for driving said finishing member.
5. In an adjustable finishing machine, the combination of a tubular column movably mounted, a nut member slidably mounted on said tubular column, a bracket mounted on said tubular column at its end, a housing swivelly mounted on said bracket, means for locking said housing against movement, a bearing assembly mounted in said housing, a shaft mounted in said bearing assembly and engaging said nut member, means mounted in said housing and adapted to rotate said shaft, a support structure rotatably mounted on said nut member, a finishing member swivelly supported by said support structure, and means for driving said finishing member.
6. In an adjustable finishing machine, the combination of a tubular column movably supported and provided with a keyway extending through its side wall, a nut member slidably mounted on said tubular column, a key secured to said nut member and engaging said keyway of said tubular column, a housing revolvably supported on said nut member and provided with a flange portion provided with a slot therein, means for clamping said housing on said nut member and extending through said slot, a support structure adjustably mounted in said housing, a finishing member swivelly supported on said support structure, means for driving said finishing member, and means for moving said nut member together with its supported mechanism longitudinally of said tubular column.
7. In an adjustable finishing machine, the combination of a tubular column, a nut member slidably mounted on said tubular column, a support structure rotatably mounted on said nut member, means for moving said nut member and its supported mechanism longitudinally of said tubular column, means for locking said support structure on said nut member, an upright shaft mounted on said support structure, a second support structure rotatably mounted on said upright
- shaft, means for locking said second support structure against movement relative to said shaft, a finishing member pivotally mounted on said second support structure, and means for driving said finishing member.
8. In an adjustable finishing machine, the combination of an upright column, a support structure rotatably mounted on said upright column, an upright shaft mounted on said support structure, a housing rotatably mounted on said support structure and around said upright shaft, said housing being provided with a bore extending substantially at right angles to the axis of said upright shaft, a bracket provided with a shaft portion swivelly mounted in said bore of said bracket, a finishing member pivotally mounted on said bracket, means for driving said finishing member, a second means for swivelly moving said bracket together with its shaft portion in said bore of said housing, a third means for locking said bracket against swivel movement, and means for moving said support structure together with its supported mechanism longitudinally of said upright column.
9. In an adjustable finishing machine, the combination of a column, a support structure movably mounted on said column, means for actuating said support structure longitudinally of said column, said means extending longitudinally of and solely through said column, a housing rotatably mounted on said support structure and adapted to rotate about the axis of said column, a bracket swivelly mounted in said housing and having its axis extending substantially at right angles to the axis of said column, a finishing member pivotally mounted on said bracket, and means for driving said finishing member.
10. In an adjustable finishing machine, the combination of a column, a support structure movably mounted on said column, means for actuating said support structure longitudinally of said column, a housing rotatably mounted on said support structure, a bracket swivelly mounted in said housing and having its axis extending substantially at right angles to the axis of said column, said bracket having an undercut portion at its lower side, a finishing member pivotally mounted on said bracket and adapted to move adjacent said undercut portion of said bracket, and means for driving said finishing member.
11. In an adjustable finishing machine, the combination of a column, a support structure movably mounted on said column, means for actuating said support structure longitudinally of said column, a housing rotatably mounted on said support structure, a bracket swivelly mounted in said housing and having its axis extending substantially at right angles to the axis of said column, said bracket having an undercut portion at its lower side, a finishing member pivotally mounted on said bracket and adapted to move adjacent said undercut portion of said bracket, means for driving said finishing member, and resilient means for actuating said finishing member toward a member to be finished.
12. In an adjustable finishing machine, the combination of a column, a support structure movably mounted on said column, a housing rotatably mounted on said support structure, a bracket swivelly mounted in said housing and provided with a boss portion, a shaft mounted in and having ends extending through said boss portion of said bracket, a second bracket piv-

ctally supported on the end portions of said shaft, a second housing secured to said second bracket, a second shaft rotatably mounted in said second housing, a finishing member fixedly secured on said second shaft, and means for driving said second shaft together with said finishing member.

13. In an adjustable finishing machine, the combination of a column, a support structure movably mounted on said column, a housing rotatably mounted on said support structure, a bracket swivelly mounted in said housing and provided with a boss portion, a shaft mounted in and having ends extending through said boss portion of said bracket, a second bracket pivotally supported on the end portions of said shaft, a second housing secured to said second bracket, a second shaft rotatably mounted in said second housing, said second shaft extending substantially parallel with said first mentioned shaft, a finishing member fixedly secured on said second shaft, means for driving said second shaft together with said finishing member, and resilient means for actuating said finishing member in a pivotal movement about said first mentioned shaft.

14. In an adjustable finishing machine, the combination of a column, a support structure movably mounted on said column, a housing rotatably mounted on said support structure, a bracket swivelly mounted in said housing and provided with a boss portion, a shaft mounted in and having ends extending through said boss portion of said bracket, a second bracket pivotally supported on the end portions of said shaft, a second housing structure secured to said second bracket, a second shaft rotatably mounted in said second housing, said second shaft extending substantially parallel with said first mentioned shaft, a finishing member fixedly secured on said second shaft, a pair of brackets pivotally mounted on said first mentioned shaft, an electrically operated unit mounted on said pair of brackets, driving means operatively connecting said electrically operated unit and said second shaft, and resilient means for actuating said finishing member in a pivotal movement about said first mentioned shaft.

15. In an adjustable finishing machine, the combination of a column, a support structure adapted to rotate about the axis of said column and to move longitudinally thereof, a housing movably mounted on said support structure and adapted to rotate about an axis extending substantially parallel with the axis of said column, a bracket swivelly supported by said housing and adapted to move about an axis extending substantially at right angles to the axis of said column, a finishing member pivotally mounted on said bracket and adapted to pivotally move about an axis extending substantially at right angles to the axis of said column, and means for driving said finishing member.

16. In an adjustable finishing machine, the combination of a column, a support structure adapted to rotate about the axis of said column and to move longitudinally thereof, a housing movably mounted on said support structure and adapted to rotate about an axis extending substantially parallel with the axis of said column, a bracket swivelly supported by said housing and adapted to move about an axis extending substantially at right angles to the axis of said column, a finishing member pivotally mounted on said bracket and adapted to pivotally move

about an axis extending substantially at right angles to the axis of said column, an electrically operated unit pivotally mounted and adapted to move about said axis around which said finishing member pivotally moves, means for adjusting the position of said electrically operated unit, and driving means operatively connecting said electrically operated unit and said finishing member, said driving means comprising belt members tensioned by the operation of said first mentioned means.

17. In an adjustable finishing machine, the combination of a column, a support structure adjustably mounted on said column to move around its axis, means for moving said support structure longitudinally of said column, a housing adjustably mounted on said support structure, a bracket swivelly mounted in said housing and provided with a boss portion having a lug fixedly connected thereto, a shaft secured in said boss portion of said bracket and having ends extending out of each side of said boss portion, a second bracket pivotally supported on said shaft and provided with a boss portion surrounding said lug of said first mentioned bracket, resilient means operatively connecting said lug of said boss portion of said first mentioned bracket and opposite sides of said boss portion of said second bracket and adapted to pivotally move said second bracket about said shaft, a second housing secured to said second bracket, a finishing member rotatably mounted in said second housing, and means for driving said finishing member.

18. In an adjustable finishing machine, the combination of a column, a support structure adjustably mounted on said column to move around its axis, means for moving said support structure longitudinally of said column, a housing adjustably mounted on said support structure, a bracket swivelly mounted in said housing and provided with a boss portion having a lug fixedly connected thereto, a shaft secured in said boss portion of said bracket and having ends extended out of each side of said boss portion, a second bracket pivotally supported on said shaft and provided with a boss portion surrounding said lug of said first mentioned bracket, resilient means operatively connecting said lug of said boss portion of said second bracket and adapted to pivotally move said bracket about said shaft, a second housing secured to said second bracket, a finishing member rotatably supported by said second housing, an electric motor assembly pivotally supported on said shaft, driving means operatively connecting said electric motor assembly and said finishing member and means for adjusting the position of said electric motor assembly to change the length of portions of said driving means.

19. In an adjustable finishing machine, the combination of a column, a support structure adjustably mounted on said column to move around its axis, means for moving said support structure longitudinally of said column, a housing adjustably mounted on said support structure, a bracket swivelly mounted in said housing and provided with a boss portion having a lug fixedly connected thereto, a shaft secured in said boss portion of said bracket and having ends extended out of each side of said boss portion, a second bracket pivotally supported on said shaft and provided with a box like portion surrounding said lug of said first mentioned bracket, resilient means operatively connecting said lug of said

- boss portion of said first mentioned bracket and opposite sides of said boss portion of said second bracket and adapted to pivotally move said bracket about said shaft, a second housing secured to said second bracket, a finishing member rotatably supported by said second housing, means for driving said finishing member, and adjustable members mounted in wall portions of said box portion of said second bracket and oppositely disposed about said lug of said first mentioned bracket, said adjustable members being adapted to engage said lug of said first mentioned bracket to prevent said resilient means from pivotally moving said second bracket about said shaft.
20. In an adjustable finishing machine, the combination of a column, a support structure rotatably mounted on said column, a housing rotatably mounted on said support structure, a bracket swivelly mounted on said housing, a shaft mounted in said bracket, a second bracket having hub portions pivotally supported on said shaft and provided with flanges at its opposite ends, said second bracket being further provided with web portions connecting said flanges and said hub portions, a second housing secured to said flanges of said second bracket, a second shaft rotatably mounted in said second housing, a finishing member fixedly secured to said second shaft and adapted to rotate therewith, a pair of bracket members pivotally mounted on said first mentioned shaft, an electric motor assembly mounted on said pair of brackets, adjustable means connecting one of said pair of brackets and one of said web portions of said second bracket and adapted to adjustably position said pair of brackets together with said electric motor assembly, a pulley member operatively driven by said electric motor assembly, a second pulley member mounted on said second shaft, and belt members connecting said pulley members.
21. In an adjustable finishing machine, the combination of an upright tubular column suitably supported, a nut member slidably mounted on said upright tubular column, a support structure rotatably mounted on said nut member, means for slidably operating said nut member on said upright tubular column, a second support structure mounted on said first mentioned support structure and adapted to swivel about a horizontal axis, a finishing member rotatably mounted and swivelly supported on said second support structure, and means for driving said finishing member.
22. In an adjustable finishing machine, the combination of a sole upright column suitably supported, a structure swivelly mounted on said sole upright column and adapted to swing entirely around the axis of said sole column, a shaft for moving said structure up and down said sole upright column, said shaft being rotatably mounted axially relative to said sole column and operatively connected with said structure, a second shaft mounted to extend transversely to the axis of said first mentioned shaft, said second shaft being operatively connected with said first mentioned shaft, a finishing member movably supported on said structure, and means for driving said finishing member.
23. In an adjustable finishing machine, the combination of an upright tubular member suitably supported and provided with a keyway extending longitudinally thereof, a nut member slidably mounted on said upright tubular member and provided with a boss portion extending

through said keyway of and within said upright tubular member, a key supported by said nut member and engaging said keyway, means for moving said nut member along said upright tubular member, said means engaging said boss portion of said nut member, a support structure supported by said nut member, a finishing member movably mounted on said support structure, and means for driving said finishing member. 5

24. In an adjustable finishing machine, the combination of a tubular member provided with a slot extending longitudinally thereof, a housing supported at one end of said tubular member, a nut member movably mounted on said tubular member and provided with a boss extending through said slot and within said tubular member, means for moving said nut member along said tubular member and comprising a shaft rotatably supported by said housing and said nut member within said tubular member, a support structure supported by said nut member, said structure being swivelly supported thereon to permit a swivel movement of said support structure entirely around said tubular member, a finishing member mounted on said support structure, 25 and means for driving said finishing member.

25. In an adjustable finishing machine, the combination of a support column, a structure movably supported by said support column, means for moving said structure along said support column, said means comprising a gear mechanism at one end of said support column and provided with means for manual operation thereof, an upright shaft mounted on said structure, a second support structure rotatably mounted on said upright shaft, a finishing member movably mounted on said second structure, and means for driving said finishing member. 30

26. In an adjustable finishing machine, the combination of a support column, slide means supporting said support column at its base, a structure movably supported by said support column, means for moving said structure along said support column and comprising manually operated means mounted at the top of said support column, a housing rotatably supported on said structure, a bracket swivelly supported by said housing, means for swivelly moving said bracket relative to said housing, a finishing member movably supported by said bracket, and means for driving said finishing member. 45

27. In an adjustable finishing machine, the combination of a support column, a structure movably mounted on said support column, means for moving said structure along said support column, a bracket rotatably supported on a horizontal axis by said structure and provided with an undercut portion adjacent its under side, a finishing mechanism pivotally supported in a vertical plane by said bracket and adapted to move 60 underneath and adjacent said undercut portion of said bracket, and means for driving said finishing member.

28. In an adjustable finishing machine, the combination of a tubular support column, a structure movably mounted on said tubular support column, means for moving said structure along said tubular support column, said means being enclosed within said tubular support column, manually operable means mounted at one end of said tubular support column and operatively connected with said first mentioned means, a bracket movably supported by said structure and provided with an undercut portion, a finishing mechanism movably supported by said bracket and 70

65

70

75

adapted to move adjacent said undercut portion of said bracket, and resilient means for driving said finishing member, and resilient means for moving said finishing member toward a member 5 to be finished.

29. In an adjustable finishing machine, the combination of a support column extending longitudinally substantially in a vertical plane, an arm structure movably supported by said support 10 structure and adapted to swing about the axis of said support column, screw means enclosed within said support column for moving said arm structure along said support column, a bracket

swivelly supported by said arm structure and adapted further to swing in a plane extending substantially at right angles to the axis of said support column, a finishing mechanism movably supported by said bracket and adapted to swing 5 in a plane located substantially parallel with the axis of said support column, and driving means for said finishing mechanism, said driving means being swivelly supported by said bracket and adapted for adjustable movement in a plane 10 located substantially parallel with the axis of said support column.

GUSTAVE A. CARLSON.
